SOUND CONTROLLING MEANS

Frederick W. Elworthy, Beverly Hills, Calif.

Application August 5, 1933, Serial No. 683,749

6 Claims. (Cl. 181—0.5)

This invention relates to means for improving the quality of the sound delivered by radio receiving sets.

It is a well known fact that in order to weaken or destroy undesirable sound waves, other sound waves may be produced which interfere with them. If the amplitudes of vibration which are produced between interfering sound waves are equal the effect may be the total mutual destruction of the waves which are caused to interfere with each other.

By this invention means are provided which take advantage of the principle just stated in such a manner as to reduce and nullify to a great extent the sound vibrations which have heretofore emanated from the casing and other parts of a radio apparatus which are adjacent to the loud speaker itself.

It is an object of the invention not only to purify and render more natural the sounds produced by the radio transmitter, but also by eliminating unnecessary and harmful sound vibrations to lengthen the life of the tubes of the transmitting set.

25 A further object of the invention is to provide a construction of radio apparatus which will cause a flow of cooler air into the casing of a radio receiving set thereby keeping the working tubes at a lower temperature and thus lengthening their working life.

While the invention is more particularly intended for use as an adjunct to radio apparatus it is not confined to such use and may be advantageously used in other situations where it is desired to reduce or eliminate undesirable sound waves.

A still further object of the invention is to provide a means which will hold sound waves emanating from the loud speaker away from the side and interior walls of the radio cabinet.

Other objects, advantages and features of the invention may hereinafter appear.

Referring to the accompanying drawing which illustrates what is at present deemed to be a preferred embodiment of the invention,

Fig. 1 is a vertical sectional view of a radio receiving set, showing the invention applied thereto.

Fig. 2 is a section on line 2—2 of Fig. 1.

50 Fig. 3 is a transverse section on line 3—3 of Fig. 2.

Fig. 4 is an elevational view of one of the sound modifying panels.

55 Fig. 5 is a sectional view on line 5—5 of Fig. 4.

Figs. 6 and 7 are fragmental elevations of mod-

ified forms of panels constructed according to the principles of the invention.

Fig. 8 is a modified sectional view in which the structure somewhat resembles that shown in Fig. 5 but certain of the cell walls are differently shaped and additional sound openings are provided.

Referring in detail to the drawing, the radio casing shown in Figs. 1, 2 and 3 is of a conventional type having a back wall 11, front wall 12, end walls 12a, floor portion 13 and a cover portion 14 the latter being hinged at 15 to the back wall 11. The sound controlling means provided by the invention consists principally of a plurality of panels, one of which is illustrated in detail by way of example in Figs. 4 and 5. This panel is shown consisting of side wall portions 16, end walls 17 and a back wall 18, there being opposite to the back wall 18 an open faced portion to deliver the modified sound waves.

Within the panel structure which has just been described are mounted a multiplicity of irregularly arranged intersecting walls 19 which combine with each other in such a manner as to produce a multiplicity of irregularly shaped cells 20, these cells each being closed on one side by the back wall 18 and being open at the opposite side. Both the panel casing and the intersecting wall construction which has been described may be made of pasteboard, cardboard or similar material.

The panel shown in Figs. 4 and 5 is designated B and this panel is included in the construction shown in Figs. 1 and 3 where it receives the same designation. The back wall 18 of this panel is directed away from the central portion of the cabinet in order that the open sides of the cells 20 may be positioned to muffle the modified sound waves toward the loud speaker S.

Describing the various other sound modifying panels shown in the drawing, next to the cover portion 14 of the cabinet is a transverse panel 21 the back wall 21a of which abuts against and is attached to the inner surface of the cover 14. At each side of this part of the casing is shown a side panel 22 likewise having a back wall 22a which abuts against the casing wall. The panels 21 and 22 are thus so arranged that the open sides of their cells are directed toward the interior of the radio cabinet. The lower edges of the panels 22 rest upon the floor or transverse partition 23 which walls off the radio set 24 from the main chamber 25 which contains the loud speaker.

Said chamber 25 is likewise provided with the upper transverse sound control panel 26, the

lower panel 27, an end panel 28 and the cross panel B which has been described in detail. These panels within the chamber 25 are each arranged with the open sides of their cells directed toward the interior of the chamber 25, the panel B being, as already stated, positioned with the open sides of its cells directed toward the loud speaker S.

Such of the panels as are located in interiorly spaced relation to the walls of the cabinet, including the inner panels 25x which are located at the sides of the loud speaker, are preferably provided with sound openings through their back walls. Thus the panel 25x is shown provided with the sound openings 25a and the panels B are shown provided with the sound openings 29.

In Fig. 6 is shown a modified form of sound control panel wherein the side walls 30 hold in place the intersecting walls 31 and 32 by which rectangular cells 33 are formed. In Fig. 7 is shown another form of the panel wherein the side walls 35 include between them three sets of intersecting cell-forming walls, these intersecting walls being designated 36, 37 and 38. By means of these intersecting walls a multiplicity of symmetrically arranged hexagonal cells 39 are produced.

Owing to the fact that a multiplicity of cell walls are provided within each of the panels, these cell walls produce a great number and variety of deflected sound waves which interfere with each other in such a manner as to greatly lessen the volume of sound produced by the more or less resonant walls of the cabinet. Furthermore these deflected sound waves will be of unequal lengths to such an extent that the deflected waves will have no vibration in any way identical with the original waves which produced them. The sound-deadening effect thus produced within the walls of the cabinet will prevent or else greatly lessen the sound waves being transmitted outwardly from the walls which enclose the cabinet. The result of this will be that a pure almost natural tone will be produced by the loud speaker as the sound waves therefrom are interpreted by the human ear.

In Fig. 8 a modified panel is shown wherein the back wall 22x is provided with large sound openings 45 and smaller sound openings 46. The cell walls 47, 48 and 49 are narrower than the depth of the panel and have openings 50 and 51 beneath them. Some of the cell walls are inclined as shown at 52.

In addition to the sound deadening devices which have already been described, a plurality of sound deadening arches or flaps 55 are arranged as indicated in Figs. 4 and 5. These flaps are preferably formed as narrow strips of pasteboard which connect the intersecting panel walls 19 between the panel backs and the open sides of the cells 20. These sound deadening flaps may be promiscuously arranged or may be grouped in whatever is found by experience to be the most efficient arrangement. The various shapes, angles and openings with which the sound-interfering flaps, walls and flanges are provided all contribute to the formation of a structure which will effectively eliminate sound vibrations behind the horn, all of which are undesirable.

A further and still more important function of the sound deadening apparatus results from the fact that the cells of the panels receive the sound waves which pass rearwardly through and from the walls of the conical loud speaker. These rearwardly directed sound waves are counteracted

by the reflecting waves which are produced when they strike against the walls of the cells of the panels. That is to say interfering sound waves are produced which nullify or muffle the backwardly directed sound waves which it is desired to destroy. Hence the waves which are directed from the loud speaker to the ear of the listener will not be accompanied by any other sounds which would interfere with their naturalness and clearness. In other words the loud speaker directs toward the listener only the set of sound waves received from the transmitter. All echo sounds are eliminated.

The sound deadening panels used must be so arranged that when combined with the loud speaker, a completely enclosed space results, in order that the sound emanating from the conical side of the loud speaker may have no opportunity to escape and interfere with the set of sound waves delivered from the inner surface of the loud speaker. The apparatus is rendered still more efficient because of the pasteboard or like material used to construct the panels being of a soft, porous, sound deadening character.

As is well shown in Figs. 1, 2 and 3, in general, the sound-deadening cells are made up of pockets having cross-sectional dimensions greater than their depth. Pockets or tubes which are a great deal deeper than their transverse dimensions will act as resonators, but the cells provided by this invention are, on the contrary, designed to deaden and eliminate all sounds except those delivered by the horn itself.

I claim:

1. In an apparatus of the kind described, the combination with a radio receiving cabinet and a loud speaker associated therewith, of a sound modifying panel located within said cabinet, said panel having a series of sound deflecting cells which open out at one face thereof, said cells having cross-sectional dimensions greater than their depth.

2. In an apparatus of the kind described, the combination with a radio receiving cabinet and a loud speaker associated therewith, of a sound modifying panel located within said cabinet, said panel having a back wall and a multiplicity of sound-modifying cells overlying said back wall and having open sides directed away from said back wall, said cells having cross-sectional dimensions greater than their depth.

3. In an apparatus of the kind described, the combination with a radio receiving cabinet and a loud speaker associated therewith, of a sound modifying panel located within said cabinet, said panel having a back wall and a multiplicity of sound-modifying cells overlying said back wall and having open sides directed away from said back wall, said cells being of various sizes and irregular shapes.

4. In an apparatus of the kind described, the combination with a radio receiving cabinet and sound delivery means associated therewith; of a plurality of sound modifying panels located within said cabinet, said panels formed independently of the walls of the cabinet having back walls and a multiplicity of cells with open sides which are directed away from said back walls, said panels being positioned within said cabinet with their back walls overlying the inner surfaces of the walls of said cabinet.

5. In an apparatus of the kind described, the combination with a walled-in compartment, and sound producing means therewithin, of a plurality of panels positioned to overlie the inner surfaces
